United States Patent Office.

WILLIAM C. GRIMES, OF PHILADELPHIA, PENNSYLVANIA.

Letters Patent No. 76,911, dated April 21, 1868; antedated April 18, 1868.

IMPROVEMENT IN FIRE-DETECTORS.

The Schedule referred to in these Letters Patent and making part of the same.

TO ALL WHOM IT MAY CONCERN:

Be it known that I, WILLIAM C. GRIMES, of Philadelphia, in the county of Philadelphia, in the State of Pennsylvania, have invented a new and useful Improvement in Fire-Indicators; and I do hereby declare that the following is a full and exact description thereof, reference being had to the accompanying drawings, and to the letters of reference marked thereon.

The object of my improvement is to give to a watchman, or other attendant employed for the purpose, the earliest indication of any fire or incipient burning in any room, hall, or building protected by or connected with the apparatus.

The nature of my invention consists in forming a tubular communication between one closed room or apartment and any number of other rooms, halls, or chambers, and in such a manner as to have an air-draught through all the tubes flowing into the one closed apartment or watch-room.

A tube, E, runs from the watch-room C to each room, hall, or chamber A A designed to be protected, and traverses more or less of the length or breadth of the apartment in which it terminates, and is in that part more or less perforated, in order to render it less liable to being closed by accident or design, and it may have a trumpet-shaped or flaring termination. The tube may be carried along the upper corners of the apartment, or elsewhere next the ceiling, and thence, in the least obtrusive way, to the watch-room, where it terminates; the orifice being more or less elevated and accessible. Above the watch-room C, rises a chimney or flue, b, whereby to obtain a natural or artificial draught. The latter may be obtained by a fire or stove kept in the watch-room for the purpose, and thus a draught through all the tubes flowing into the watch-room may be maintained.

Figure 1 is a vertical section or elevation of a series of rooms or chambers having tubular communications with the watch-room above.

Figure 2 is a vertical transverse section of fig. 1—

Like letters of reference being used for the same parts in all the figures.

A A, rooms, halls, or chambers; C C, watch-room; D D, passages; E E, connecting or communicating-tubes; F F, sections of hose; G, water-pipe; H, well for hose; b, chimney; e e, perforated part of the tubes.

In a suitable or convenient position upon each floor, I place one or more sections of hose F, and pipe of an aggregate length sufficient to reach every room or apartment upon that floor. These are connected with a water-pipe or some suitable fountain, G, so as to be always ready for use at a moment's warning. The hose, when not in use, may be dropped in a doubled form into a deep well or tube, H, or may be wound on a reel.

Use of the apparatus: A watchman or suitable person occupies the watch-room constantly, and should a fire commence in any of the rooms connected by a tube therewith, he will be apprised thereof by the odor of burning. A moment's attention at the tubes will determine from what room it emanates, the rooms and tubes being numbered. The watchman at once repairs to the room, being provided with the proper keys, and, with the hose at hand, he is amply able to quench any incipient burning.

What I claim as my invention, and desire to secure by Letters Patent, is—

A series of tubes converging from several apartments of a house to one apartment, and adapted for the transmission of aeriform fluids to this centre, substantially as shown and described, and for the purpose set forth.

WM. C. GRIMES.
